P. J. KELLY

INDUCTANCE COIL

Filed March 22, 1924

UNITED STATES PATENT OFFICE.

PATRICK J. KELLY, OF PHILADELPHIA, PENNSYLVANIA.

INDUCTANCE COIL.

Application filed March 22, 1924. Serial No. 701,194.

To all whom it may concern:

Be it known that I, PATRICK J. KELLY, a citizen of the United States, residing at Philadelphia, in the county of Philadelphia and State of Pennsylvania, have invented certain new and useful Improvements in Inductance Coils, of which the following is a specification.

This invention relates to tuning inductances, and more particularly to a device for tuning and transforming a signal energy in a radio receiving circuit, for increasing the efficiency of the circuit.

An object of the invention resides in providing an inductance having a plurality of coils arranged for cooperation and constructed in predetermined proportions adapted to be interposed in the antennæ, plate, and grid and filament circuits of an audion bulb type of receiving set, the coils cooperating to transform and amplify the signals received in the antennæ circuit for increasing the distant range of reception of the set, and increasing the amplification of the signals in the circuit.

Another object of the invention resides in providing an inductance coil comprising a stationary tube member provided with a secondary winding, arranged in spaced sections of equal inductive value on the tube, a primary superposed on the secondary, and formed of spaced sections of predetermined inductance value, and equal in each section, having a predetermined relation with the sections of the secondary, and arranged in a special relation to the secondary section, the primary being connected in the antennæ section, and the secondary in the filament and grid circuits of a radio receiving set of the audion bulb type, while a movable coil member is rotatably mounted within the tube, on an axis extending between the sections of the secondary coil, and which last mentioned coil is also formed in spaced sections of equal inductive value, and adapted for connection in the plate and phone circuit of the receiving set, in order to produce a cooperation with the stationary primary and secondary coils, so that signals received in the primary circuit will be transformed and amplified in the secondary coil, and the movable coil, for obtaining a maximum range of reception in the set and amplification in the receiving circuit.

The invention also includes other objects and improvements in the details of construc-

tion and assemblage of parts, which are more particularly pointed out in the following description and claims, directed to a preferred form of the invention, it being understood, however, that variations may be made in this construction, without departing from the principal and essential elements of the invention as described and claimed.

In the drawing, forming a part of this application:

Figure 1 is a side elevation of the inductance coil constructed according to the invention.

Figure 2 is a vertical transverse section therethrough.

Figure 3 is a wiring diagram, showing the manner of interposing the coils of an inductance in the radio receiving circuit.

A tubular member is indicated at 1, which forms a mounting for the several parts of the invention, and on which is mounted the secondary inductance winding indicated at 2, which is arranged in separated sections 3 and 4 respectively, which contain a substantially equal number of strands of wire, in order that the inductive value of each section 3 and 4 will be substantially equal. Sections 3 and 4 of the secondary winding, 70 are mounted at substantially equal distances from the ends of the tubular member 1, while the space between the coil sections is substantially equal or slightly less than the width of each section, this distance being 75 predetermined, in accordance with the number of strands of wire, in each section, for obtaining the most efficient results, the connecting wire between the two sections having substantially a half turn, as indicated 80 at 5, which will not materially affect a functioning of the coil sections. The ends of the secondary winding, indicated at 6 and 7 respectively, are extended through openings 85 in the tubular member and longitudinally 85 of the same to the bottom end of the member, where they are connected with suitable binding posts 8, arranged in spaced relation on the lower edge of said member 1.

A primary winding 9 is superposed in concentric relation, on the secondary winding 2, and is provided with sections 10 and 11, having substantially an equal number of turns arranged in spaced relation to one another, one section being superposed on each of the sections of the secondary winding, as

clearly shown in Figures 1 and 2, a half turn 12 joining the sections in the intermediate portion of the member, as shown. The primary winding is formed of a larger gauge 5 wire than the secondary winding, and has considerably fewer turns, so that the space occupied by the winding is substantially half of that occupied by the secondary winding, the sections 10 and 11 of the primary winding 10 being arranged with corresponding ends adjacent corresponding ends of the secondary winding, as shown in Figure 1, which has been found to produce the most efficient cooperation between the two windings. The 15 ends of the primary windings 9 are extended through openings in the tubular member 1, as indicated at 13, and directed longitudinally along the interior of the member, and are connected to binding posts or other suitable 20 terminals 14, arranged in spaced relation at the lower end of the tubular member 1, and opposite the terminals 8 of the secondary coil, for receiving the circuit connecting wire for properly interposing the 25 primary winding in the antennae circuit.

Bracket members 15 are mounted at diametrically opposite sides of the tubular member 1 between the sections of the primary and secondary windings, which are formed 30 of a single piece of sheet material. Each bracket member has an arcuate base portion 16 adapted to fit the tubular member, and conform to the curvature thereof, and which is secured to the tubular member by suitable 35 means indicated at 17, the central portion of the base 16 having outwardly extending parallel projections 18, the lower one of which is formed with an opening 19, adapted to receive and provide a bearing for the 40 spherical head 20, on the rotatable bearing members 21. As clearly illustrated in the drawings, the bearing members 21 fit between the projections 18, the resiliency of which retains the spherical heads in the 45 respective bearings through the cooperation of the openings 19 therewith, and which frictionally engage the heads with sufficient force to provide a perfect electrical conduit. Set screws 22 are mounted in opposite ends 50 of the projections 18, and are adapted to adjust the tension of these bearing members on the spherical head. Each of the bearing members 21 receive shaft extensions 23, carried by a movable member 24, and which extend 55 through openings 25, at diametrically opposite points in the tubular member 1. The movable member 24 is of tubular form, and smaller in diameter than the tubular member 1, and mounted in said member 1, 60 so that in the position shown in Figure 2, the members are concentric, and the axis of rotation of the movable member extends midway between the coil sections 3 and 4 of the secondary coil on the tubular member 1. The axis of the movable member 4 extends 65

through the central portion thereof, and the member receives a coil winding 26, which is arranged in sections 27 and 28, of equal inductive value, at opposite sides of the axis 23 of the movable member, so that the movable coil will cooperate with the stationary coils of the movable member 1. The ends of the coils 26 are extended through openings in the movable member 24, and connected, as indicated at 29, with suitable terminals carried by the ends of each shaft section 23, so that an electrical circuit is provided to the bearing members 15 through the shaft and the spherical head 20. Suitable terminals are provided on each bearing member, as indicated at 30, with which the proper circuit wire for the removable coil may be connected. One of the bearing members is provided, at the end of the upper extension 18 with a vertically extending terminal portion 31, which receives screws 32, in threaded engagement therewith, for mounting the bar assembly on the back of an instrument board indicated at 33, of a radio receiving set, while one of the shaft sections 30 34 has an extension 34, which projects through an opening 35 in the panel 33 for receiving a suitable form of operating handle 36, so that the movable core may be rotated on its axis within the stationary tubular member 1 and the stationary coils carried thereby for effecting a tuning action 35 in the corresponding circuit when the member is rotated, through the operation of the handle 36. 40

The wiring diagram in Figure 3 shows one form of application of the invention to a radio receiving set, and in which the primary coil 9 is connected in the antennae ground circuit, by having the antennae lead in wire, and the ground wire connected to the respective binding posts 14, for this purpose. The secondary coil 2 on the tubular member 1, is connected in the grid and filament circuit of the set by suitable 45 connections 37 and 38, a variable condenser having a vernier being indicated at 39, interposed in parallel with the stationary coil 2, and which is adapted for tuning the circuit containing the coil. One terminal of the movable coil 26 is connected by a wire 40, with one terminal of the phones indicated at 41, while the other terminal of the movable coil is connected by a wire 42, with the plate of the audion bulb 43. The A and B batteries indicated at 44 and 45 respectively, are interposed in the circuit in the manner illustrated for functioning in connection with the tube 43 in the well known manner. 50

From the above description, it will be seen that an induction coil has been provided for use in radio receiving sets, wherein the primary and stationary secondary are in such an intimate concentric relation, that substantially weak currents in the primary 55 60 65 70 75 80 85 90 95 100 105 110 115 120 125 130

will be effectively transformed in the secondary, and through the impressed voltage therein produce a substantially amplified current in the secondary for building up the field to the coil, which will be further received and transformed in the movable coil 26, so that a maximum amplification in the phone circuit will result to enable signals of a considerably weak nature in the primary to be effectively received, so that the normal receiving range of the audion bulb will be effectively increased, together with the increased amplification of the sounds produced in the phones 41.

15 What is claimed is:

1. An inductance coil for radio receiving apparatus comprising a secondary stationary inductance, formed in a pair of separated sections mounted in axial alignment, 20 a primary winding formed in a pair of sections superposed on the sections of the secondary winding in concentric relation, and a movable inductance coil of smaller size than the first mentioned coil rotatable on an 25 axis extending between the sections of the first mentioned coil.
2. An inductance coil for radio receiving apparatus including a tubular member, a secondary coil mounted on said tubular 30 member and arranged in spaced sections thereon, a primary coil formed of sections superposed on the sections of the secondary winding, binding posts mounted in spaced relation on the tubular member and having 35 the ends of the respective coils connected thereto, bearing members mounted at diametrically opposite points on the tubular member, a movable member having shaft extensions rotatably mounted in bearing 40 members, said bearing members and shaft extensions extending between the sections of the primary and secondary coils on said tubular member to position the axis of rotation of the movable member centrally be- 45 tween the sections of said coils, and a movable coil mounted on the movable member,

and having electrical connections with the shaft extensions and the bearing members which provide terminals for the movable coil.

50 3. An inductance coil comprising a pair of independent superposed concentric stationary coils, said coils being formed in separate sections in axial alignment, said sections being formed of a continuous winding, 55 the inner coil having a substantially greater inductive value than the outer coil, and the sections of the outer coil being disposed over one end portion of the sections of the inner coil.

60 4. A three circuit inductance coil comprising a pair of stator coils, one of said stator coils being formed of a pair of separated sections of continuously wound wire, the sections being joined by substantially a 65 half turn of said wire, the other stator coil being formed in a pair of sections directly wound on the first mentioned stator section, the last mentioned stator coil being formed of a continuous winding having the sections 70 joined by a half turn of the winding substantially overlying the half turn of the first mentioned stator winding, and a rotor coil 75 movable on an axis extending between the stator coil sections.

80 5. A three circuit inductance coil comprising a cylindrical coil support, an inner stator coil directly wound on said support, an outer stator coil directly wound on the inner stator coil, said coils having the end portions extended through said support to the interior thereof, said end portions being positioned against the inner face of the coil supports and extending outwardly toward the end portion thereof, the terminals of the ends 85 of the said coils being extended outwardly through the end portions of said coil support beyond the ends of the inductance coils on said support for connection with terminals carried by said support.

90 In testimony whereof I affix my signature.

PATRICK J. KELLY.
